ELECTRICAL RECORDING AND INDICATING INSTRUMENT

Samuel J. Koch, Great Neck, and Charles Ehrlich, New York, N.Y., assignors to Pyramid Instrument Corporation, Lynbrook, N.Y., a corporation of New York

Filed Aug. 16, 1961, Ser. No. 66,380

Term of patent 14 years

(Cl. D26—14)

FIG. 4.

FIG. 3.

FIG. 1.

FIG. 5.

FIG. 2.

FIG. 6.

FIG. 7.

FIG. 1 is a front view of an electrical recording and indicating instrument, showing our new design.

FIG. 2 is a side view thereof.

FIG. 3 is a bottom view thereof.

FIG. 4 is a top view thereof.

FIG. 5 is a rear view thereof.

FIG. 6 is a perspective view thereof.

FIG. 7 is an enlarged fragmentary view of the upper left portion of FIG. 4.

The dominant features of our new design are shown in solid lines in the drawing.

We claim:

The ornamental design for an electrical recording and indicating instrument, substantially as shown and described.
